(57) **CLAIM**

The ornamental design for a ladder safety guard, as shown and described.

DESCRIPTION

FIG. 1 is a front side perspective view of a ladder safety guard, showing our new design;

FIG. 2 is a back side elevation view thereof;

FIG. 3 is a front side elevation view thereof;

FIG. 4 is a right side elevation view with the left side elevation view being a mirror image thereof; and,

FIG. 5 is a bottom plan view with the top plan view being a mirror image thereof.

1 Claim, 5 Drawing Sheets

FIG. 1

FIG. 2

FIG. 3

FIG. 4

FIG. 5
